PERMUTATION LOCK

Ivan A. Ladizinsky, Cleveland, Ohio

Application February 21, 1938, Serial No. 191,609

9 Claims. (Cl. 70—133)

This invention relates, as indicated, to permutation locks, but has reference more particularly to a lock of this character which is peculiarly adapted for personal use.

5 The primary object of the invention is to provide a lock of the character described, the combination of which can be easily and quickly changed.

Another object of the invention is to provide a 10 lock of the character described, the combination of which can be changed without the use of tools, without taking the lock apart and without resorting to any parts of the lock other than those which are external of the casing and can be 15 readily manipulated.

A further object of the invention is to provide a lock of rugged construction, and consisting of a minimum number of inexpensively manufactured parts.

20 To the accomplishment of the foregoing and related ends, said invention then, consists of the elements hereinafter fully described and particularly pointed out in the claims.

The annexed drawing and the following description set forth in detail certain mechanism embodying the invention, such disclosed elements constituting, however, but one of various mechanical forms in which the principle of the invention may be used.

25 30 In said annexed drawing:

Fig. 1 is an elevation of the lock;

Fig. 2 is a vertical cross-sectional view of the lock, taken on the line 2—2 of Fig. 1;

35 Fig. 3 is a cross-sectional view of the lock, taken 35 on the line 3—3 of Fig. 2, but with various parts omitted to more clearly show the base of the lock.

40 Fig. 4 is a view similar to Fig. 2, but with the parts as they appear when the bolt has been partially projected through the casing of the lock;

Fig. 5 is a horizontal cross-sectional view of the lock, taken on the line 5—5 of Fig. 3;

Fig. 6 is a perspective view of one of the rack-bar retaining cups; and

45 Fig. 7. is a perspective view of the other rack-bar retaining cup.

Referring more particularly to the drawing, the lock will be seen to comprise a casing which is adapted to fit within a mortise or recess in a 50 door and which consists of a base 1 and a cover 2, the base and cover, after the assembly of the various parts being secured together in any desired manner as by rivets, welding, or the like.

The base 1 is provided with a pair of upstanding abutments 3 adjacent which the bolt 4 of

the lock is disposed, the bolt being slidably mounted on the base and provided at one side with gear teeth 5 engaged by a pinion 6. The pinion 6 has a trunnion 7 which extends through the cover 2 of the casing and has secured thereto, as by a 5 set screw 8, a knurled knob 9, the pinion being thereby rotated to cause one end of the bolt 4 to be projected from and retracted into the casing, as indicated in Fig. 3.

Mounted within a recess 10 in the base 1 for 10 sliding movement in a direction transverse to that of the bolt 4 is a latch or rack-bar 11 provided at one end with gear teeth 12 in mesh with the pinion 6. This rack bar has a limited degree of longitudinal movement between the ends 13 15 and 14 of the recess 10, and is provided in its upper surface with a series of transversely extending equally-spaced grooves or recesses 15, 16 and 17 of equal depth, and with similar recesses 18 and 19, respectively, disposed between 20 the recesses 15 and 16 and 16 and 17, the recesses 18 and 19 being of somewhat less depth than recesses 15, 16 and 17. The bar 11 is further provided adjacent one end with an elevated portion formed by two oppositely sloping surfaces 20 and 25 21.

The recess 18 is intersected in its medial portion by concentric circular grooves or recesses 22 and 23 which are formed in the base 1, but are not as deep as the recess 10. Disposed within the 30 recess 22 is the annular flange 24 of a cup-like member 25 which is also provided with a smaller annular flange 26 having a beveled surface 27 at one end. The flange 24 has a portion thereof cut away to provide a recess 28 which is of a 35 length equal to the width of the rack bar 11, which extends radially from the flange 24 and serves a purpose to be presently described.

A similar cup-like member 30 is provided, having an annular flange 31 extending into the recess 23, and a smaller annular flange 32 having a beveled surface 33 at one end. The flange 31 of the member 30 is cut away to form a recess 34 of the same length as the recess 28 in the flange 24. The member 30 is also provided with a small 45 knob or button 35 (Figs. 5 and 6), which serves a purpose hereinafter explained.

The members 25 and 30 are retained in position by the flange 36 of a rotatable cup-like member 37 which extends through the cover 2 50 of the lock and has threadedly secured thereto a dial 38. The dial 38 has an index mark 39 at one point adjacent its periphery, and this mark is used in conjunction with the usual graduations 40 on the cover 2 of the lock for deter- 55

mining the movements of the dial 38 required to open the lock.

The member 37 has a square aperture in its center through which extends the square shank 41 of a coupling member 42. The member 42 has an axial bore 43 through which extends the cylindrical shank 44 of a second coupling member 45. The member 45 has a pointed member 46 projecting therefrom and into abutment with the rack bar 11, and the shank 44 has a reduced portion 47 of square cross-section extending therefrom and into an aperture 48 of corresponding cross-section in the base of a knurled dial 49 which extends through the dial 38 and is rotatable independently of the latter. The dial 49 is provided at one point adjacent its periphery with an index mark 50, this mark being used in conjunction with graduations 51 on the dial 38 for determining the movements 20 of the dial 49 required to open the lock.

A spring washer 52 is interposed between the inner surface of the dial 49 and the member 37, and this spring tends to normally hold the dial 49 in its outermost position, as shown in 25 Figs. 2 and 4.

Secured to the base 1, directly behind the member 45, as by means of a screw 53 is a spring 54, which bears against the member 45 and serves a purpose to be presently described.

30 Mounted between the recesses 22 and 23, on the base 1, for pivotal movement in a direction transverse to the plane of the base are a pair of oppositely disposed dogs 55 and 56, which are of a width corresponding to the length of the recesses 18 and 19, being designed to enter the recess 18 when the lock is closed, and the recess 19 when the lock is open. These dogs are normally held in the depressed position shown in Fig. 5 by means of flat springs 57 and 58 respectively. Each spring has one end secured to its dog at a point on the upper surface of the dog and its other end bearing freely on the surface of the base 1. The intermediate portion of each spring is bowed, and the bowed portion of the spring 57 is designed to be engaged by the button 35. The bowed portion of the spring 58 is designed to be engaged by the pin 29. The function of these dogs will be presently described.

50 The operation of the lock will now be briefly described. It will be assumed that the lock is closed, the bolt 4 projecting from the casing as indicated in dotted lines in Fig. 3, and that it is desired to open the lock, that is, retract the bolt so that it lies entirely within the casing. In the closed condition of the lock, the flanges 24 and 31 of the members 25 and 30, respectively, are disposed within the grooves 15 and 16 of the bar 11, thereby preventing movement 60 of the bar, and rotation of the knob 9 for the purpose of retracting the bolt 4.

In order to open the lock, it is necessary to align the recesses 28 and 34 with the rack-bar 11, so that the rack-bar can be moved by the 65 knob 9 downwardly to the position shown in Fig. 3, the bolt 4 being retracted at the same time. In order to align the recesses 28 and 34 with the rack-bar, the dials 49 and 38 must be turned either clockwise or counter-clockwise to 70 the marks selected for the combination on the graduated scales 51 and 40, respectively. In turning the dial 49, the member 25 is simultaneously turned, through the intermediary of the coupling member 45, which is in frictional engagement with the inner surface of the flange

26 thereof. In turning the dial 38, the member 30 is simultaneously turned through the intermediary of the member 37 and coupling member 42, the latter being in frictional engagement with the inner surface of the flange 32 of the member 30. It will be understood that since the dial 38 is movable, the graduations 51 thereon are also movable, and that it is accordingly necessary to always first set the dial 38 when opening or closing the lock. 10

In moving the rack bar to the position shown in Fig. 3, the sloping surface 20 of such bar engages the pointed member 46 of the coupling member 45, pushing the latter as well as the coupling member 42 from the position shown in Fig. 2 to the position shown in Fig. 4, thereby uncoupling the dials 49 and 38 from the members 25 and 30 respectively. If a person should now inadvertently or purposely turn the dials 49 and 38, without first depressing the dial 49, 20 no harm will ensue, since the members 25 and 30 remain stationary, unless coupled with these dials. To avoid a contingency wherein the dials 49 and 38 are thus turned and the dial 49 then depressed so as to couple the members, it is 25 advisable, after the lock has been opened as aforesaid, to immediately depress the dial 49, so that the members will be coupled and the lock in a condition in which it cannot be tampered with. In turning the dials after the dial 49 has 30 been thus depressed, the flanges 24 and 31 of the members 25 and 30 will respectively enter the recesses 17 and 16 in the rack bar, and lock the bar against upward movement, so that it will only be necessary to reset the combination 35 in order to raise the bar to close the lock.

Where the dial 49 has been depressed, and the dials 49 and 38 thereby coupled with the members 25 and 30, if it is desired to close the lock, it is only necessary to set the dials 49 and 38 at the desired positions forming the combination, whereupon the bar 11 may be elevated to its uppermost position. In the course of thus elevating the bar, by means of the knob 9, the sloping surface 21 of the bar engages the pointed member 46 of the coupling member 45, pushing the latter, as well as the coupling member 42 from the position shown in Fig. 2 to the position shown in Fig. 4, thereby uncoupling the dials 49 and 38 from the members 25 and 30 respectively. After the lock has been thus closed, it is necessary to immediately depress the dial 49, so that the members will be coupled and the lock in a condition in which it cannot be tampered with. After the dial 49 has been thus 55 depressed, the dials should be turned to lose the settings, and the lock cannot be again opened, except by one who knows the combination.

The frictional contact between the coupling members and the inner surfaces of the flanges 26 and 32 is sufficient for rotating the members 25 and 30, but is not so great as to render difficult the uncoupling of the members. The beveled surfaces 27 and 33 are of value in centralizing and guiding the coupling members to their coupling position when the dial 49 is depressed. If desired, gear teeth may be provided on the flanges 26 and 32 and on the coupling members to assure a more positive driving connection. The spring 54 prevents engagement of the coupling members with the cups, except at such times when the dial 49 is depressed. 60

The combination of the lock may be changed as often as desired, and for this purpose, it is only necessary, when the bar 11 is freely movable 75

in its recess, to reset the dials to the new combination and then depress the dial 49 to couple the members. In other words, the combination of the lock may be changed without taking the lock apart or manipulation of any parts inside the lock casing, as is required in the usual types of permutation locks.

The dogs 55 and 56 are designed to prevent tampering with the lock, or unauthorized opening thereof. But for the presence of these dogs, if one of the dials was properly set for opening, which would be possible if a person tried setting the dial at each graduation successively, the lock could be opened by slowly rotating the other dial and at the same time applying tension to the bar 11. He could then pull the bar through the recess 28 or 34 when such recess became properly aligned with the bar. However, by using the dogs 55 and 56, such possibility of opening the lock is minimized, since by exerting tension on the bar 11 while trying to open the lock, the dogs will not be elevated from the recess 19, even when the springs 57 and 58 are engaged by the button 35 and pin 29 respectively. In other words, the dogs will not be released, unless there is no tension on the bar 11.

Other modes of applying the principle of my invention may be employed instead of the one explained, change being made as regards the structure herein disclosed, provided the means stated by any of the following claims or the equivalent of such stated means be employed.

I therefore particularly point out and distinctly claim as my invention:—

35 1. In a lock of the character described, a bolt and means for controlling the movements of said bolt, said means comprising a plurality of cup-like members, dials for rotating said members, and coupling members interposed between said dials and cup-like members, said coupling members being coaxial with and movable into and out of engagement with said cup-like members.

40 2. In a lock of the character described, a bolt, and means for controlling the movements of said bolt, said means comprising flanged rotatable members, dials coaxial with said members, and members movable by one of said dials into engagement with said flanged members for coupling the latter with said dials.

45 3. In a lock of the character described, a bolt, and means for controlling the movements of said bolt, said means comprising flanged rotatable members, dials coaxial with said members, and members movable by one of said dials into engagement with said flanged members for coupling the latter with said dials, and spring means opposing the movement of the dial-movable members.

50 4. In a lock of the character described, a bolt,

and means for controlling the movements of said bolt, said means comprising a bar having spaced recesses therein, rotatable members having flanges movable in said recesses, dials for each of said members, and members movable by one of said dials into engagement with said flanged members for coupling the latter with said dials, and means on said bar for moving said coupling members out of engagement with said flanged members.

5 5. In a lock of the character described, a bolt, and means for controlling the movements of said bolt, said means comprising a bar having spaced recesses therein, rotatable members having flanges movable through said recesses, dials for each of said members, members movable by one of said dials into engagement with said flanged members for coupling the latter with said dials, spring means opposing the movement of the dial-movable members, and means associated with said bar for moving said coupling members out of engagement with said flanged members.

10 6. In a lock of the character described, a bolt, and means for controlling the movements of said bolt, said means comprising a bar having spaced recesses therein, rotatable members having flanges movable through said recesses, dials for each of said members, members movable by one of said dials into engagement with one of said flanged members, said member having a square shank and an axial bore therethrough, and a member movable by the same dial into engagement with another of said flanged members, said last-named member having a cylindrical shank extending through said bore.

15 7. In a lock of the character described, a bolt, and means for controlling the movements of said bolt, said means comprising a bar having spaced recesses therein, rotatable members having flanges movable through said recesses, dogs normally held in one of said recesses in the bar for preventing movement of the bar, means responsive to the movements of said flanged members, when in desired position, for releasing said dogs from said recess, said dogs being released only when no tension is exerted on said bar.

20 8. In a lock of the character described, a bolt, and means for controlling the movements of said bolt, said means comprising a rotatable member, a dial coaxial with said member, and a member movable by said dial into engagement with said first-named member for coupling the latter with said dial.

25 9. In a lock of the character described, a bolt, and means for controlling the movements of said bolt, said means comprising a bar, tumblers for preventing movement of said bar, and auxiliary latch means for preventing movement of said bar.
